UNITED STATES PATENT OFFICE.

WILLIAM HENRY RODDEN, OF TORONTO, ONTARIO, CANADA.

BARB FOR WIRE FENCING.

SPECIFICATION forming part of Letters Patent No. 379,729, dated March 20, 1888.

Application filed April 22, 1887. Serial No. 235,813. (No model.) Patented in Canada May 4, 1887, No. 26,588.

To all whom it may concern:

Be it known that I, WILLIAM HENRY RODDEN, of the city of Toronto, in the county of York and Province of Ontario, Canada, have 5 invented certain new and useful Improvements in Barbs for Wire Fencing, (on which I have obtained a patent in the Dominion of Canada, No. 26,588, dated the 4th of May, 1887;) and I do hereby declare that the following is a full, 10 clear, and exact description of the same.

My invention consists of a barb applicable to all kinds of wire fencing, and also to fence-wires, whether of one or more strands.

My barb is formed of a piece of metal of, 15 say, about three eighths of an inch in width, with ends parallel to each other and at a sharp angle to the sides.

I make it (by rolling or otherwise) with one side (that which comes next the wire strand 20 or longitudinal) flat and the other or outside face corrugated or waved, the ridges running lengthwise with the strip. To form the points I split the above blank at both ends in the 25 crease or thinnest part of the corrugated metal, as seen at $a^3 a^3$, the length of such splits regulating the length of the barb-points.

For full comprehension of the invention reference must be had to the annexed drawings, in which—

30 Figure 1 is a view of the barb, split and ready for coiling upon the wire; Fig. 2, a section of same, and Fig. 3 a view of the barb in place.

Similar letters of reference indicate like 35 parts.

A is the barb-blank, of any desired length

and of the outline shown, $a a$ and $a' a'$ being the split ends.

B B are the longitudinal wires, upon one of which my barb is fixed by first placing its central part, a^2 , diagonally against the single wire, and then twisting, coiling, or winding it thereupon until the four ends or points $a a' a' a$ project in different directions, as seen in Fig. 3.

I use a barb one side of which is, as shown 45 in Fig. 2, made with a waved, ridged, or corrugated surface, A', as the flat side A^2 will fit the longitudinal closely, while the other side, being convex, will give strength to the barb, besides insuring sharp points instead of the 50 "chisel-points," which are produced by severing a flat blank in this way. By my invention the barb-points assume their proper position during the act of coiling and do not require special adjustment.

Having thus described my invention, I beg 55 to state that what I claim is as follows:

The combination, with a fence wire, of the four-pointed barb A, the same being formed from a blank rhomboidal in shape, flat upon 60 one side and corrugated upon the other, and having a longitudinal incision, a^3 , at each end in the thinnest portion of the metal, said barb having its central part coiled around the wire in such manner that the four points will project in different directions, substantially as set forth.

WILLIAM HENRY RODDEN.
